(57) **CLAIM**

The ornamental design for a deer attracting device, as shown and described.

DESCRIPTION

FIG. 1 is an illustration of a perspective view of a deer attracting device;

FIG. 2 is an illustration of another perspective view thereof;

FIG. 3 is an illustration of a front view thereof;

FIG. 4 is an illustration of a rear view thereof;

FIG. 5 is an illustration of a side view thereof;

FIG. 6 is an illustration of another side view thereof;

FIG. 7 is an illustration of a plan view thereof;

FIG. 8 is an illustration of a bottom view thereof;

FIG. 9 is an illustration of a perspective view of another deer attracting device;

FIG. 10 is an illustration of another perspective view thereof;

FIG. 11 is an illustration of a front view thereof;

FIG. 12 is an illustration of a rear view thereof;

FIG. 13 is an illustration of a side view thereof;

FIG. 14 is an illustration of another side view thereof;

FIG. 15 is an illustration of a plan view thereof; and,

FIG. 16 is an illustration of a bottom view thereof.

The broken lines in the figures represent portions of the deer attracting device that are not part of the claimed design.
